UNITED STATES PATENT OFFICE.

EVERETT D. MORETON, OF ERIE, PENNSYLVANIA.

PROTRACTOR.

1,107,983.

Specification of Letters Patent. Patented Aug. 18, 1914.

Application filed April 18, 1914. Serial No. 832,788.

To all whom it may concern:

Be it known that I, EVERETT D. MORETON, a citizen of the United States, residing at Erie, in the county of Erie and State of Pennsylvania, have invented new and useful improvements in Protractors, of which the following is a specification.

This invention relates to drafting instruments and in particular to limb protractors of the type wherein each instrument includes a flat body of sheet material having a semi-circular recess, and a movable blade having a flat head pivotally mounted within the body recess, the blade and body being constructed so that their adjacent broad faces are absolutely flush.

The primary object is to provide a securing device for use in locking the movable blade in angularly adjusted position with relation to the body, which device is constructed and mounted within the instrument in such a manner that it will be highly efficient in use but will not at any point project past the broad faces of the body or blade. The instrument may thus be used either side up and the body thereof is constructed with its base edges at right angles to each other, thereby making it particularly convenient for use in dividing circles, traversing angles, drawing oblique lines at right angles to each other, laying off given angles on each side of a line without changing the setting, and in various other capacities which should be apparent to persons skilled in the use of such an instrument.

The invention consists in the features of construction, combination and arrangement of parts, hereinafter fully described and claimed, reference being had to the accompanying drawings, in which:

Figure 1 is a top plan view of the device, the cam lever being shown in its operative position in full lines and in its inoperative position in dotted lines; Fig. 2 is a sectional view on line 2—2 of Fig. 1; and Fig. 3 is a detail perspective view of the locking member.

In the drawing, the numeral 1 designates the flat body of the protractor which is constructed of sheet material and is provided with a circular recess 2 in which the flat head 3 of the movable blade 4 is mounted in the usual manner, the head 3 being provided with a marginal scale 5 of angular measure-

ment and upon the body contiguous thereto with a vernier 6 reading to five minutes. The body 1 is provided as usual with recesses 7 of considerable area adjacent to the corners thereof, whereby the weight of the material is reduced, and the head 3 of the blade 4 is likewise cut away, one of the head recesses 8 being coextensive with the scale and the adjacent edges of the head and body recesses being cut concentric to the axis of the blade pivot.

The head of the blade is provided with a circumferential slot 9 opening through its outer edge and being in communication with the recess 8, and the body is provided with a radially disposed opening 10 in that portion of the body which intervenes between the large recess 2 and the medially disposed one of the recesses 7. This opening is adapted to align with the slot 9 of the blade head. The flat shank of a locking member 11 is adapted to extend through the said opening and slot. The inner end of this member is broadened to provide a head 12 equal in thickness to the blade head and affording shoulders 13 for engagement with the concave wall of the said recess 8. The opposite end of the locking member projects into the medially disposed body slot 7 where it is embraced by the bifurcated portions 14 of the active end of a cam lever 15, which is pivotally connected to the said end of the locking member by means of the pivot pin 16. The lever 15 is provided upon the bifurcated portions of its active end with beveled cam faces 17 for engagement with the correspondingly beveled edge faces 18 of the body recess, whereby tension will be placed upon the locking member, when the cam lever is in its operative position in prolongation of the said member, as shown in full lines in Fig. 1, to lock the head 3 of the movable blade in adjusted position within the receiving body recess. The said blade head may therefore be mounted loosely within the recess so that it may be operated therein with little friction. When the cam lever is moved into the dotted line position in Fig. 1, it will be inoperative and the movable blade will be released to permit the desired adjustment thereof. The said lever also is constructed equal in thickness to the body of the instrument so that no portions of the locking device will project above or below

the upper and lower faces of the body, thus enabling the instrument to lie flat upon either of its faces.

What is claimed is:

5. 1. In a protractor of the class described, the combination of a flat body having a circular recess therein opening through one of its edges, a movable blade equal in thickness to the body and having a circular head rotatably mounted within the circular recess, the blade head being provided with a recess and with an arcuate slot communicating with the said recess and opening through the outer periphery of the head, the said body being provided with a second recess adjacent to the circular recess and with an opening leading radially from the circular recess into the second recess, the said opening being adapted to register with the slot 65 of the blade head, a locking member extending through the said slot and opening and having a head disposed within the recess of the blade head, the outer end of the locking member being extended into the second recess, and a cam lever pivotally mounted upon the outer end of the locking member and having a cam face for engagement with the inner edge of the said second recess.
2. In a protractor of the class described, the combination of a flat body having a circular recess therein opening through one of its edges, a movable blade equal in thickness to the body and having a circular head rotatably mounted within the circular recess, the blade head being provided with a recess and with an arcuate slot communicating with the said recess and opening through the outer periphery of the head, the said body being provided with a second recess adjacent to the circular recess and with an opening leading radially from the circular recess into the second recess, the said opening being adapted to register with the slot 80 of the blade head, a locking member extending through the said slot and opening and having a head disposed within the recess of the blade head, the outer end of the locking member being extended into the second recess, and a cam lever pivotally mounted upon the outer end of the locking member and having a cam face for engagement with the inner edge of the said second recess.
3. In a protractor of the class described, the combination of a flat body having a circular recess therein opening through one of its edges, a movable blade equal in thickness to the body and having a circular head rotatably mounted within the circular recess, the blade head being provided with a recess and with an arcuate slot communicating with the said recess and opening through the outer periphery of the head, the said body being provided with a second recess adjacent to the circular recess and with an opening leading radially from the circular recess into the second recess, the said opening being adapted to register with the slot 95 of the blade head, a locking member extending through the said slot and opening and having a head disposed within the recess of the blade head, the outer end of the locking member being extended into the second recess, and a cam lever pivotally connected thereto, the said end portions of the lever being provided with cam faces for engagement with the inner edge of the second recess.
4. In a protractor of the class described, the combination of a flat body having a circular recess therein opening through one of its edges, a movable blade equal in thickness to the body and having a circular head rotatably mounted within the circular recess, the blade head being provided with a recess and with an arcuate slot communicating with the said recess and opening through the outer periphery of the head, the said body being provided with a second recess adjacent to the circular recess and with an opening leading radially from the circular recess into the second recess, the said opening being adapted to register with the slot 100 of the blade head, a locking member extending through the said slot and opening and having a head disposed within the recess of the blade head, the outer end of the locking member being extended into the second recess, and a cam lever pivotally connected thereto, the said end portions of the lever being provided with cam faces for engagement with the inner edge of the second recess, the inner edge of the second recess being oppositely beveled adjacent to the said opening and the cam faces of the lever being correspondingly beveled for engagement therewith.
5. In testimony whereof I affix my signature 115 in presence of two witnesses.
